UNITED STATES PATENT OFFICE.

HARRY L. TURNER, OF PORTLAND, OREGON.

AERIAL CONVEYER SYSTEM.

Application filed June 3, 1924. Serial No. 717,557.

This invention is designed in the main to accomplish the purposes set forth in an application filed by me Apr. 10, 1924, Serial No. 705,597 and as in said application it is of particular advantage in the handling of logs and the invention is exemplified in connection with such use although it will be understood that other materials may be used. In describing the invention, therefore, I have given to the different parts and lines the designations usually applied to such parts in the logging industry but it will be understood that the use of such designations is a matter of convenience rather than a limitation of the invention to this particular operation.

The invention involves the use of a standing line or support and a travelling carrier on the support which can be moved along the standing line to any point desired. It involves a skidding line operating over the carrier with means to pull slack on the skidding line at the point desired and devices for locking the skidding line with the carrier to carry the logs to the destination desired and means for releasing the skidding line to deposit the log at such point, the device being capable of gathering the logs at any point along the standing line and of depositing the logs at any point along the standing line. Features and details of the invention will appear from the following specification and claims.

The invention is illustrated in the accompanying drawings as follows:

Fig. 1 shows a perspective view of a logging system.

Fig. 2 a central section of the carrier on the lines 2-2 in Figs. 3 and 4.

Fig. 3 a section on the line 3-3 in Fig. 2.

Fig. 4 a section on the line 4-4 in Fig. 2.

Fig. 5 a plan view of the logging or hoisting engine operating the lines of the system.

1 marks the head tree which is guyed by the usual lines 1^a, and 2 the tail tree which is guyed by the usual lines 2^a. The standing line 3 is supported on a shoe 4 on the tail tree and secured at an anchor 5. The standing line is supported on the head tree by a jack 6 mounted on the head tree and terminates at one of a set of blocks 7, the other of the blocks being connected by an anchor line 8 to some convenient anchorage. A heel line 10 is run through the block 7 over a pulley 11 secured to the head tree by a strap 12 and extends to a heel block 112 on the logging engine 13. It will readily be seen by operating the heel line

the standing line may be given any tension desired. While I have shown a standing line as a support for the carrier, it will be understood that any convenient support may be used and need not be in the form of a flexible cable as shown.

A carrier 14 is mounted on the standing line 3 and a skidding line 15 leads through the carrier from the logs or load 16 to a block 17 mounted by means of a strap 18 on the head tree. The skidding line is carried to a skidding drum 19 on the engine. The hold-back or trip line 20 extends from the carrier through a block 21 on the tail tree and through a corner block 22 secured by a strap 23 on an anchorage 24 and thence through a block 25 secured by a strap 26 on the head tree to the trip line drum 27 on the engine.

A grip line 20^a extends from the carrier to a grip drum 23^a. It is guided by a sheave 21^a carried by a strap 22^a on the head tree. The purpose of this line is to control a clamp for locking the skidding line with the carrier.

A slack pulling line 28 is secured by a swivel 29 to the skidding line and carried through a sheave 30 on the carrier, and thence through a block 31 secured to the head tree by a strap 32 to a slack pulling line drum 33 on the engine.

The carrier is pulled out by the trip line 20, the skidding line, grip line and pull back line being played out with it and when the carrier reaches a position opposite the logs the hold back line 20 is locked and the tension on the grip line increased. This releases the skidding line and slack is pulled by the slack pulling line 28 so that the free end of the skidding line can be carried to the load. The load is engaged and the skidding line is pulled in so as to lift the load to the position desired. The grip line is then operated (by releasing tension in this instance) to lock the skidding line with the carrier. The load is then brought to the desired destination by pulling in the skidding line, the grip line and slack pulling lines following in as the skidding line is pulled in and the trip line being played out as the skidding line is pulled in. When the logs are at the destination the trip line is locked and the grip line is put under increased tension thus releasing the skidding line and the load is lowered to the position desired by playing out the skidding line.

The mechanism for accomplishing these operations so far as the carrier is concerned is as follows: The carrier is carried by grooved

wheels 34. These are mounted on axles 35 secured between side plates 36. A sheave 37 is journaled on a pin 38 secured to the side plates 36 by extensions on which nuts 39 are placed.

5 The skidding line extends between jaws 40 and 41 of a locking clamp and thence through guide sheaves 42 and 43 carried by pins 44 and 45 between the plates.

The clamp is provided with the removable 10 working surfaces 46 which are secured in the clamp jaws by means of screws 47. A series of toggle bars 48 are arranged along the jaw 41 and are pivotally connected therewith by pins 49. The opposite ends of these bars or 15 levers are mounted on pins 50 secured in an anchor plate 51. The anchor plate has extensions 52 which extend to the side plates and the anchor plate is secured between the side plates by a series of bolts 53. Supporting 20 plates 54 are secured to the side plates by rivets 55 and form shoulders at their upper edges making a more secure base for the anchor plate 51 in order to sustain the severe strain to which the anchor plate is subjected.

25 The jaw 40 is mounted on a series of bars 55 which are pivotally connected with the jaw by pins 56. The opposite ends of the levers or bars 55 are mounted on pins 57 which are secured in the anchor plate 58. The anchor 30 plate 58 has the side extensions 59 and the plate is secured to the side plates by bolts 60. Supporting plates 61 are secured to the side plates by rivets 62 and form engaging shoulders for the anchor plate.

35 In order to limit the movement of the jaws and prevent the toggle levers straightening I provide a stop. This is formed by a lug or block 63 secured between the side plates and having a bolt 63^a extending through it.

40 Washers or shims 64 are arranged under the head 65 of the bolt so as to vary or adjust the stop and the bolt is secured in place by a nut 66. It will be understood that the bars 48 are arranged at each side of the jaw 41. The end 45 bars 48 are extended forming levers 67. The anchor plate is cut away at 68 and the supporting plate 61 is cut away at 69 affording a passage next to the side plates for these levers. A link 70 is arranged between the ends 50 of the levers 67 and connected thereto by a pin 71. The opposite end of the link 70 extends between the arms of a forked lever 73 and is connected thereto by a pin 72. The lever 73 is mounted on a pin 74, this pin having a 55 head or nut 75 at one side and is secured by a nut 76 at the opposite side. The end bars of the series of bars 55 are extended forming levers 77. A link 78 is arranged between the ends of these levers and connected thereto by a pin 79. The opposite end of the link 78 extends between the arms of a forked extension of the lever 73 and is connected with the lever 73 by a pin 80. It will readily be seen that 60 as the lever 73 is swung the jaws 40 and 41 are swung to and from the skidding line.

The means for swinging the lever 73 and thus setting the clamp or strip on the skidding line is as follows:

A rod 81 extends through a guide block 83 which guide block is secured by bolts 84 between the plates 36. A spring 85 is anchored on the block 83 and operates against a collar 86 mounted on the rod 81 and adjustably secured thereon by a nut 87. A pin 82 extends through a slot 88 in one of the side plates 75 and a bar 89 is secured to the outer end of the pin 82 and extends along the side plate through a guide 90, the guide being secured to the plate by bolts 91. The line 20^a is secured to the bar 89. The trip line is secured 80 to the carrier by a bail 92 which is secured to the plates by a pin 93.

In the operation of the carrier, the carrier is stopped at the desired point and the grip line is put under tension so as to overcome 85 the spring 85. This swings the lever 73 clockwise and opens the jaws 40 and 41 through the lever connections before described. The skidding line is released and slack pulled through the slack pulling line. 90 The load is then engaged and the skidding line pulled out giving the load the desired position, tension being preferably kept on the grip line so as to maintain the jaws of the clamp in open position. When the log or 95 load has reached the desired position the tension on the grip line is decreased sufficiently to permit the spring to close the jaws. The skidding line is then pulled in, the trip line being played out as desired. As the load 100 comes on the clamp it tends to increase the clamping action so that any tendency of the skidding line to slip under the force of the load is obviated. When the carrier reaches the desired position for depositing the load 105 the trip line is set and the tension is put on the grip line and the skidding line is preferably given a slight movement to assist the grip line in opening the jaws. The jaws then move to their open position and are held in 110 this position by the grip line and the skidding line is played out to deposit the load as desired.

The frame of the engine 13 is made up of the side beams 94 connected by cross beams 115 95 in the usual manner. As shown it is provided with a boiler 96. Engines 97 are secured to the frame and operate on cranks 98. The cranks are mounted on the drive shaft 99, this shaft being journaled in bearings 100 120 on the side beams and an intermediate beam 94^a.

Gears 101 and 102 of different diameters mesh with gears 103 and 104 respectively to give different speeds and the gears 103 and 104 are locked with a shaft 106 by means of a clutch mechanism 105 actuated by a friction actuated mechanism 107 on the end of the shaft, this mechanism being similar to and operating as shown in my Patent #1,362,373, 130

Dec. 14th, 1920. A gear 108 meshes with the gear 101. The gear 108 is mounted on a shaft 109 carried by bearings 110. The heel block drum 112 has a clutch 111 which 5 can be locked with the gear 108 by means of a friction device 113 at the end of the shaft 109. The heel block drum is also provided with the usual brake 114. The operation of this drum is apparent and is used simply to 10 put the tension in the standing line.

A gear 115 is mounted on the shaft 106 and meshes with an internal gear 116. The internal gear 116 is adapted to be locked by means of a clutch 117 with the skidding drum 15 19. The gear 116 and drum 19 are mounted on a shaft 118 mounted in bearings 119. The clutch 117 is operated by a friction device 120 at the end of the shaft. A brake 117^a is provided for the skidding drum and 20 is operated by a rod 117^b actuated by a foot lever 117^c.

A gear 121 meshes with the gear 102. It is mounted on a shaft 122 and the shaft 122 is mounted in bearings 123. The trip line drum 25 27 is mounted on the shaft 122 and is adapted to be locked with the shaft by a clutch 124, the clutch being actuated by a friction device 126. A brake band 128 operates on a brake surface 127 on the drum. The brake band is actuated 30 by a shaft 129. A rock arm 130 operates the shaft 129, the rock arm being actuated by a ram 131. The ram is supplied through a pipe 132 controlled by a variable pressure fluid controlling valve 133. Through this valve, 35 which may be of any of the usual types, varying pressure may be delivered to the ram as desired so as to give the brake pressure desired, to lock or control the load through the trip line. This is of importance in that where 40 logs are carried down steep slopes the hold-back or trip line is depended upon to prevent the log running away and one of the particular advantages of my construction is that the skidding line is locked in the carrier under 45 all conditions and cannot be released when the log moves ahead of the carrier by reason of ground contour. The gear 121 is fixed on the shaft 122 and meshes with a gear 134 on an intermediate shaft 135. The shaft 135 is mounted in bearings 136. A gear 137 is 50 fixed on the shaft 135 and meshes with a gear 138. The gear 138 is mounted on a shaft 139. The shaft is mounted in bearings 140 in the frame. The slack pulling line drum 33 is 55 mounted on the shaft 139 and is in frictional engagement with the gear 138 at all times. A friction plate 141 is arranged on the side of the gear 138 and opposes a friction plate 142. A friction lining 143 is arranged between 60 these plates. The plate 142 is mounted on the side of the drum. At the opposite side of the drum there is a friction plate 144 opposing a friction plate 146 with an intervening friction material 145 between these plates. 65 A driver 147 is splined on the shaft 139. The

gear 138 is also fixed on the shaft so that the driver moves with the gear. The driver is moved through the action of a spring 148 arranged between the driver and a collar 149. A pin 150 extends through the shaft and engages a collar and is actuated by a push pin 151 extending through the end of the shaft. The push pin is actuated by a head 152, the head being subjected to the action of a diaphragm 153 in a diaphragm case 154. Pressure is maintained on this diaphragm at all times so that the friction surfaces between the drum and the gear and the drum and the driver are maintained at all times. The pressure may, however, be very much modified if it is desired to carry the normal tension on the slack pulling line just sufficient to keep the line under tension but insufficient to pull the slack. The diaphragm is controlled 70 through a pipe 156 which extends to a control valve 157, this control valve being of the variable pressure control type. The drum 33 has under all conditions a higher speed than the skidding drum 19, the gearing 102, 121, 134, 137 and 138 giving quite a preponderance of 75 speed to the slack pulling line drum over the drum 19. Consequently the tensions I have heretofore described are maintained on the slack pulling line as the skidding line is actuated so the slack pulling line is maintained 80 normally under tension sufficient to take the slack out of the line itself. If this is not sufficient and it is desired to pull slack additional pressure may be gotten through the control valve to the diaphragm and thus sufficient 85 tension to be placed on the slack pulling line to pull slack. Somewhat the same mechanism is employed with regard to the grip line 90 20^a. Opposing friction faces 158 and 159 are arranged on the gear 138 and drum 23^a 95 respectively with a friction disc 159 between them. Opposing friction faces 160 and 161 are arranged at the opposite end of the drum with a friction disc 162 between them, the 100 face 160 being secured to the drum and the opposite face to a driver 163. The driver is splined on the shaft 139. A spring 164 is arranged between the driver and a collar 165 and its pressure is exerted against against 105 the friction surfaces to keep them in engagement. A pin 166 arranged through a shaft operates on the collar and a friction device 167 operates on the pin. The friction device is fluid actuated and is controlled through 110 a pipe 168 extending to a variable pressure control valve 169. In this device the normal tension on the grip line is not sufficient to overcome the tension of the spring but is simply sufficient to keep the slack out of the line. When, however, the control valve 169 is operated 115 to give a greater pressure added tension is placed on this line sufficient to overcome the spring and unlock the clamp.

The operation of the device is as follows: The operator sets the trip line drum 27 and 130

this pulls the carriage out into the field. During this time the skidding line is retarded by the brake 117^a and the grip line is retarded because the gear 138 rotates the drums 33 and 23^a in a direction tending to wind up the grip and pull in lines. The friction created by the diaphragms is controlled by the valves 157 and 169 is set very light during this operation—just sufficient to keep the slack out of the lines going out but not sufficient in the grip line to operate the spring 85. When the carriage reaches its destination the trip line drum is released from the clutch and locked by the brake. High pressure is put on the clutches controlling the grip line drum 23^a so as to give sufficient tension to the grip line to overcome the spring 85. The skidding line is released sufficiently to permit the slack pulling by the slack pulling line and this may be accomplished by the added pressure through the valve 157 if desired. When the load is engaged the skidding line drum is set and raises the load to the desired position. The high tension on the grip line is then released and this permits the spring to set the clamp. The brake on the trip line is then released and the load is drawn in by the skidding line, the slack in the pull in and grip lines being taken up by the added speed of the drums controlling these lines. When the carriage reaches the point desired the trip line is locked and the grip line subjected to high pressure releasing the clamp. If desired the skidding line may be given a slight forward movement to assist in releasing the clamp. The skidding line is then played out lowering the load by the manipulation of the brake. After the deposit of the load the skidding line is pulled back to the position desired and the high tension released on the grip line, thus locking the skidding line with the carriage and the carriage is then drawn out through the action of the trip line.

What I claim as new is:—

1. In an aerial conveyer system, the combination of a carrier support; a carrier on the support; a skidding line running to the carrier; a trip line running to the carrier and opposed to the skidding line; means operating from a fixed point and at different positions of the carrier on the support locking the skidding line with the carrier and against the pull of the load and releasing said line from the carrier; and independent means operating from a fixed point for pulling the slack of the skidding line.

2. In an aerial conveyer system, the combination of a carrier support; a carrier on the support; a skidding line running to the carrier; a trip line running to the carrier and opposed to the skidding line; means for locking the skidding line with the carrier and against the pull of the load and releasing said line from the carrier; a control line operating said means; and a slack pulling line pulling the

slack of the skidding line, said lines being operated from the same point.

3. In an aerial conveyer system, the combination of a carrier support; a carrier on the support; a skidding line running to the carrier; a trip line running from the carrier; a control line leading to the carrier; a slack pulling line leading to the carrier; an apparatus for operating said lines to move the carrier to and hold the same at various positions on the support; and means actuated through the action of said lines and at different points on the support at the will of the operator locking against the pull of the load intermediate portions of the skidding line as desired with and releasing the same from the carrier and pulling slack in the skidding line while released.

4. In an aerial conveyer system, the combination of a carrier support; a carrier on the support; a skidding line running to the carrier; a clamp on the carrier directly engaging and locking the skidding line with the carrier and against the pull of the load; a control line operating said clamp; and a slack pulling line pulling the slack of the skidding line, said lines being operated from the same point.

5. In an aerial conveyer system, the combination of a carrier support; a carrier on the support; a control apparatus on the carrier; a skidding line running to the carrier; a skidding drum actuating the skidding line; a control line running to the carrier and actuating the control apparatus; a slack pulling line running to the carrier and pulling the slack of the skidding line; a control drum actuating the control line; and a continuously yielding driving mechanism for the control drum.

6. In an aerial conveyer system, the combination of a carrier support; a carrier on the support; a control apparatus on the carrier; a skidding line running to the carrier; a skidding drum actuating the skidding line; a control line running to the carrier and actuating the control apparatus; a slack pulling line running to the carrier and pulling the slack of the skidding line; a control drum actuating the control line; a continuously yielding driving mechanism for the control drum; a slack pulling line drum actuating the slack pulling line; and a continuously yielding driving mechanism for the slack pulling line drum.

7. In an aerial conveyer system, the combination of a carrier support; a carrier on the support; a control apparatus on the carrier; a skidding line running to the carrier; a skidding drum actuating the skidding line; a control line running to the carrier and actuating the control apparatus; a slack pulling line for pulling slack in the skidding line; a slack pulling line drum actuating the slack pulling line; and a continuously yield-

ing driving mechanism for the slack pulling line drum.

8. In an aerial conveyer system, the combination of a carrier support; a carrier on the support; a control apparatus on the carrier; a skidding line running to the carrier; a skidding drum actuating the skidding line; a control line running to the carrier and actuating the control apparatus; a slack 10 pulling line for pulling slack in the skidding line; a slack pulling line drum actuating the slack pulling line; and a continuously yielding driving mechanism for the slack pulling line drum, said driving mechanism giving 15 the slack pulling line drum a greater speed than the skidding drum.

9. In an aerial conveyer system, the combination of a carrier support; a carrier on the support; a control apparatus on the carrier; a skidding line running to the carrier; a skidding drum actuating the skidding line; a control line running to the carrier and actuating the control apparatus; a slack 20 pulling line running to the carrier and pulling 25 the slack of the skidding line; a control drum actuating the control line; a continuously yielding driving mechanism for the control drum; a slack pulling line drum actuating the slack pulling line; and a continuously 30 yielding driving mechanism for the slack pulling line drum, said driving mechanisms giving to the control drum and the slack pulling line drum greater speeds than the skidding line drum.

35 10. In an aerial conveyer system, the combination of a carrier support; a carrier on the support; a control apparatus on the carrier; a skidding line running to the carrier; a skidding line drum actuating the skidding line; a control line running to the carrier and actuating the control apparatus; a control drum actuating the control line; a continuously 40 yielding driving mechanism for the control drum; devices varying the driving force of the mechanism; and a slack pulling line pulling slack with the skidding line.

45 11. In an aerial conveyer system, the combination of a carrier support; a carrier on the support; a control apparatus on the carrier; a skidding line running to the carrier; a skidding line drum actuating the skidding line; a control line running to the carrier and actuating the control apparatus; a control drum actuating the control line; a continuously 50 yielding driving mechanism for the control drum; devices varying the driving force of the mechanism; a slack pulling line pulling slack with the skidding line; a slack pulling line drum actuating the slack pulling line; and a yielding driving mechanism for the slack pulling line drum.

60 12. In an aerial conveyer system, the combination of a carrier support; a carrier on the support; a control apparatus for the carrier;

a skidding line running to the carrier; a skidding line drum actuating the skidding line; a control line running to the carrier and actuating the control apparatus; a slack pulling line running to the carrier and pulling slack 70 in the skidding line; a slack pulling line drum actuating the slack pulling line; a continuously yielding driving mechanism for the slack pulling line drum; and devices varying the driving force of the mechanism. 75

13. In an aerial conveyer system, the combination of a carrier support; a carrier on the support; a skidding line running to the carrier; a trip line running to the carrier; a control line running to the carrier; a slack 80 pulling line running to the carrier; and means operated from a fixed point in connection with said lines holding the carrier at various positions on the support at the will of the operator, locking and releasing the skidding line 85 with and from the carrier comprising a continuously yielding driving mechanism for the slack pulling line.

14. In an aerial conveyer system, the combination of a carrier support; a carrier on the support; a skidding line running to the carrier; a strip line running to the carrier; a control line running to the carrier; a slack pulling line running to the carrier; and means operated from a fixed point in connection with 90 said lines holding the carrier at various positions on the support at the will of the operator, locking and releasing the skidding line with and from the carrier comprising a continuously yielding driving mechanism for the slack pulling line and a continuously actuating mechanism for the control line. 95

15. In an aerial conveyer system, the combination of a carrier support; a carrier on the support; a skidding line running to the carrier; a trip line running to the carrier; a control line running to the carrier; a slack pulling line running to the carrier; and means operated from a fixed point in connection with 100 said lines holding the carrier at various positions on the support at the will of the operator, locking and releasing the skidding line with and from the carrier comprising a continuously yielding driving mechanism for the slack pulling line and a continuously actuating mechanism for the control line. 105

16. In an aerial conveyer system, the combination of a carrier support; a carrier on the support; a skidding line running to the carrier; a trip line running to the carrier; a control line running to the carrier; a slack pulling line running to the carrier; a clamp on the carrier controlled by the control line 110 adapted to engage and lock the skidding line with the carrier; and a continuously actuated yielding driving mechanism for the slack pulling line. 115

17. In an aerial conveyer system, the com- 120

bination of a carrier support; a carrier on the support; a skidding line running to the carrier; a trip line running to the carrier; a control line running to the carrier; a slack pulling line running to the carrier; a clamp on the carrier controlled by the control line adapted to engage and lock the skidding line with the carrier; a continuously actuated yielding driving mechanism for the slack pulling line; and a continuously actuated yielding driving mechanism for the control line.

18. In an aerial conveyer system, the combination of a carrier support; a carrier on

the support; a skidding line running to the carrier; a trip line running to the carrier; a control line running to the carrier; a slack pulling line running to the carrier; a clamp on the carrier controlled by the control line adapted to engage and lock the skidding line with the carrier; a continuously actuated yielding driving mechanism for the slack pulling line; and means for varying the driving force of said mechanism.

In testimony whereof I have hereunto set my hand.

HARRY L. TURNER.
